UNITED STATES PATENT OFFICE.

ALBERT WEBER, OF SEATTLE, WASHINGTON, ASSIGNOR OF ONE-HALF TO JOHN HAKANSON, OF KING COUNTY, WASHINGTON.

CUTTER-HEAD.

1,317,113.

Specification of Letters Patent. Patented Sept. 23, 1919.

Application filed July 15, 1918. Serial No. 244,871.

To all whom it may concern:

Be it known that I, ALBERT WEBER, citizen of the United States, residing at Seattle, in the county of King and State of Washington, have invented certain new and useful Improvements in Cutter-Heads, of which the following is a specification.

This invention relates to improvements in cutter heads and has for its principal object to provide an improved and novel design of cutter head which locks the knives between concentric plates; to provide, in a cutter head, a plurality of concentric plates some of which have annular ribs and means for binding notched knives intermediate the plates with the notches coöperating with the ribs. In cutter heads it is necessary that the knives be held securely both radially and laterally and that they be secured positively against accidental release from the head. Our improved cutter head accomplishes the above results.

Other objects will appear as my invention is more fully explained in the following specification, illustrated in the accompanying drawings and pointed out in the appended claim.

In the drawings Figure 1 is a side elevation, with parts broken away of my cutter head. Fig. 2 is a bottom plan view of the top plate of my assembled head. Fig. 3 is a plan view of a knife plate of my head. Fig. 4 is a side elevation, with parts broken away, of a companion cutter head. Fig. 5 is a plan view of the assembled plates of Fig. 4 taken along line $\alpha-\alpha$. Fig. 6 is a plan view of knives for the head shown in Figs. 4 and 5. Fig. 7 is a side elevation of Fig. 6.

Referring more particularly to the drawings numeral 1 indicates a tubular core having a shouldered portion 2. The small end of core 1 is threaded as at 3. In operation the core sets over a belt driven spindle 4 to which it is held by means of set screws 4. In Figs. 1 to 3 inclusive a plain bottom plate 5 fits on to the core 1 against shoulder 2 and next to bottom plate 5 a knife plate 6 fits on to core 1. Knife plate 6 has knife slots 7 in its periphery to receive knives 8 which are set on edge and project beyond the plate on either side. A ribbed plate 9 fits over core 1 and has an annular rib 10 which fits into notches 11 in knives 8. Plate 9 also has knife slots 7 to receive knives 12. The knife

slots 7 are the same in plates 6 and 9 but receive different knives as shown for cutting a bead or tongue on the edge of a board. A ribbed top plate 13 is threaded on to core 1 and has an annular rib 14 which fits into notches in knives 12 similar to the notches 10 in knives 8. Plates 5 and 13 are provided with set screw holes 15 to receive set screws 16. In operation the head is assembled, with the knives in place as just described and shown in Fig. 1 with the top plate screwed down tight. The set screws 16 are then tightened so as to lock the top plate against unscrewing and to grip the knives 8 between plates 5 and 9 and the knives 12 between plates 6 and 13. This gripping of the knives prevents lateral movement or chattering, while coöperating ribs on the plates and notches on the knives prevent the knives from flying from the head even though loosened.

Referring to Figs. 4 and 7, inclusive, which illustrate a companion cutter head for cutting the groove in the side of a board as in flooring, numeral 17 indicates a bottom plate which is similar to bottom plate 5 except that it has alternate set screws 18 and countersinks 19 the latter of which permit of a set screw being passed through it. A slotted knife plate 20, similar to plate 6 except that it has threaded set screw holes for set screws 21, is next placed upon core 1. Adjacent knife plate 20 a thin knife plate 22 is placed on core 1. Plate 22 has knife slots 23 adapted to receive a wide facing knife 24 and a narrow grooving knife 25 adjacent each other. An annular groove 26 extends around plate 22 in order to leave room for a rib 27 which is a part of a ribbed knife plate 28 and which engages a notch 29 in knife 25. Plate 28 is provided with knife slots which coöperate with the wide knife portion of slots 23. A top plate 30 similar in every way to top plate 13 screws on to core 1 and completes the head by employing set screws for locking the knives. In the latter head the facing knives are clamped between plates 17 and 30 with the holding rib on plate 30 and the knives 24 are clamped between plates 20 and 28 with the rib on plate 28. It will be noted that the knives in all cases are positively gripped and can not become detached from the cutter head except by considerable loosening of the plates.

While I have shown a particular form of embodiment of my invention, I am aware that many minor changes therein will readily suggest themselves to others skilled in the art without departing from the spirit and scope of my invention and I therefore desire to avoid being limited to the exact form shown and described.

Having described my invention, what I claim as new and desire to protect by Letters Patent, is:—

A cutter head comprising, a tubular core provided near one end with a shoulder and having its opposite end screw threaded, means to clamp the tubular core upon a stationary supporting element, a plate provided with an opening to loosely receive the tubular core and adapted to contact with the shoulder, a knife plate having an opening to loosely receive the core and provided with slots extending through its top and bottom and through its edge, knives ar-

ranged within the slots and projecting above the knife plate and having transverse grooves, a clamping plate having an opening to loosely receive the tubular core and provided with a laterally extending flange to enter the grooves, a plate having a screw threaded opening to snugly receive the screw threaded portion of the tubular core, and bolts engaging within transverse screw threaded openings in the last named plate and adapted to engage with the clamping plate to force the same into proper holding engagement with the knives, said bolts also serving as means to lock the last named plate against accidental rotation.

In testimony whereof I affix my signature in the presence of two witnesses.

ALBERT WEBER.
